DESCRIPTION

FIG. 1 is top perspective view of a spill resistant tab for drink-through lids.

FIG. 2 is a front side view of a second embodiment for a spill resistant tab.

FIG. 3 is a back side view of a second embodiment for a spill resistant tab.

FIG. 4 is a left side view of a second embodiment for a spill resistant tab.

FIG. 5 is a right side view of a second embodiment for a spill resistant tab.

FIG. 6 is a top plan view of a second embodiment for a spill resistant tab; and,

FIG. 7 is a bottom plan view of a second embodiment for a spill resistant tab.
